UNITED STATES PATENT OFFICE.

CLIFFORD O. POOLE, OF COBDEN, ILLINOIS.

WRENCH.

1,378,719.

Specification of Letters Patent. Patented May 17, 1921.

Application filed August 20, 1919. Serial No. 318,718.

To all whom it may concern:

Be it known that I, CLIFFORD O. POOLE, citizen of the United States, residing at Cobden, in the county of Union and State of Illinois, have invented certain new and useful Improvements in Wrenches, of which the following is a specification, reference being had therein to the accompanying drawing.

10 This invention relates to new and useful improvements in wrenches, and especially in the provision of a wrench so arranged that a tool held in the socket thereof may be operated around the corners, or in such places 15 where an ordinary wrench is inaccessible.

The invention comprises a simple and efficient device of this nature, having various details of construction, combination and arrangement of parts which will be herein- 20 after fully described, shown in the accompanying drawings and then specifically defined in the appended claim.

25 My invention is illustrated in the accompanying drawings which, with the letters of reference marked thereon, form a part of this application, and in which:

Figure 1 is a side elevation showing the application of my invention.

Fig. 2 is an end view.

30 Fig. 3 is a sectional view through a sprocket chain and gear connections between the bitstock and socket stock.

Fig. 4 is an edge view of Fig. 3, and

35 Figs. 5 and 6 are detail views of the casing in which the sprocket chain and gear connections are mounted.

Reference now being had to the details of the drawings by letter:

40 A designates a bitstock having a crank handle B, and C is a breast plate swiveled to one end, these features being common to the ordinary stock. One end of the bitstock is squared, as at D and its end is provided with a threaded aperture adapted to receive 45 a screw F passing through a clamping plate H. Fitted over the end of the bitstock is a casing, details of which are shown in Figs. 5 and 6 of the drawings, and which is made up of two parts, the casing proper being 50 designated by letter I, and the covering by letter J. Said casing has integral lugs I' projecting therefrom along its marginal edge, and which are adapted to engage similar shaped recesses formed in the marginal 55 edge of the cover, and affording means whereby the cover may be held from lateral

movement when adjusted in place. The cover and casing are provided with registering apertures N through which a screw O is adapted to pass, the apertures in the cover 60 being threaded to engage the threads of the screw to hold the parts securely together.

Journaled in registering apertures in the casing and cover is a hub Q of a sprocket wheel Q'. Said hub has a square outlined 65 opening Q² therein adapted to fit over the squared portion D of the bitstock. When the hub is adjusted in the casing and the casing placed over the bitstock, the plate H is held clamped against the face of the cover 70 by means of the screw F, as shown clearly in the drawings.

A wrench socket P is journaled in other registering apertures in the casing and cover, and the wrench socket has an integral 75 sprocket wheel P' about which and the sprocket wheel, a sprocket chain passes. The wrench socket has an annular beading P² about its circumference which is adapted to contact with the cover to hold the socket 80 in one direction, while a plate S having a central aperture clamps against the face of the casing and is held in such position by means of a screw S' passing through an aperture in the plate S and engaging a 85 threaded hole in the end of the socket.

When the parts are assembled as shown in Fig. 1 of the drawings, it will be noted that by turning the bitstock, the wrench socket is adapted to engage the nut, or other object, 90 and may be rotated in such position as would be inaccessible by the use of an ordinary wrench, and by reason of the gears being of different sizes, the rotary movement imparted to the bitstock may be accelerated. 95 It will be noted that the sprocket wheel upon the bitstock is of less diameter than the sprocket wheel upon the part engaging the bit, or nut to be turned. The difference in leverage between the two wheels enables 100 the application of increased torque to the part to be turned over than possible if the driving and driven wheels were of the same diameter.

What I claim to be new is:

105 A wrench comprising an oblong casing with integral lugs on the edge thereof, a cover with recesses to receive said lugs, said casing and cover having registering openings therein, a bit socket journaled in said openings and having an annular shoulder adapted to bear against a flange about one of said 110

openings, a plate fastened to one end of said socket and bearing against the face of the casing, a sprocket wheel rotating with said socket, a bitstock having an end journaled in openings in the casing and cover, a sprocket wheel rotating with the portion of the bitstock within the casing, and a sprocket chain passing about said wheels, the diameter of the driven sprocket being

greater than that of the driving sprocket for the purpose of obtaining increased torque.

In testimony whereof I hereunto affix my signature in presence of two witnesses.

CLIFFORD O. POOLE.

Witnesses:

H. C. KOHLER,
J. W. THOMAS.
